UNITED STATES PATENT OFFICE.

AUGUSTUS BAUS, OF NEW YORK, N. Y., ASSIGNOR TO AUGUSTUS BAUS & CO., OF SAME PLACE.

AGRAFFE FOR PIANOS.

SPECIFICATION forming part of Letters Patent No. 314,310, dated March 24, 1885.

Application filed May 26, 1884. (No model.)

To all whom it may concern:

Be it known that I, AUGUSTUS BAUS, of the city, county, and State of New York, have invented a new and Improved Agraffe, 5 of which the following is a full, clear, and exact description.

The object of my invention is to provide a new and improved agraffe which is so constructed that under no circumstances the 10 strings can slip in the same, and are at all times held firmly and securely, and by thus securely holding the said strings the tuning-pins are relieved of a part of the immense 15 strain they are subjected to in pianos of the usual construction, and thereby necessitating less frequent tuning of the instrument. The invention consists in the construction and arrangement of parts, as will be hereinafter fully described and claimed.

Reference is to be had to the accompanying drawings, forming part of this specification, in which similar letters of reference indicate corresponding parts in all the figures.

Figure 1 is a face view of my improved agraffe. Fig. 2 is a side view, parts being broken out and others shown in section; and Fig. 3 is a face view of an agraffe for double strings, and Fig. 4 is a perspective view of an agraffe for treble strings.

30 A cylindrical head, A, formed on the upper end of a screw, B, of greater or less length,

is provided with a vertical groove or recess, D, forming two upwardly-projecting prongs, E and E'. In each prong E or E' one, two, or three apertures, a, are formed, according 35 to the number of strings the agraffe is to hold. The apertures a in the two prongs are arranged at different elevations, and the apertures are inclined, as shown. The outer ends of the apertures a are widened or enlarged, as shown, 40 so as to prevent cutting the strings.

The agraffes are screwed into the wrest-plank or into the metal plate, the agraffes 45 screwed into the wrest-plank having long screws and those screwed into the plate having short screws.

The strings being held in both prongs cannot slip, and are at all times held taut and firmly.

Having thus described my invention, I claim 50 as new and desire to secure by Letters Patent—

An agraffe having two prongs, each provided with an inclined aperture or inclined apertures, the central axes of the two corresponding apertures in two prongs being on 55 one and the same line, substantially as herein shown and described.

AUGUSTUS BAUS.
